Primary Examiner — Susan Moon Lee*(74) Attorney, Agent, or Firm* — Sean Christian Connolly(57) **CLAIM**

The ornamental design for a round bale hay feeder, as shown and described.

DESCRIPTION

FIG. 1 is a perspective view of a round bale hay feeder of the present design;

FIG. 2 is a front view of a round bale hay feeder of the present design;

FIG. 3 is a rear view of a round bale hay feeder of the present design;

FIG. 4 is a side view of a round bale hay feeder of the present design; and,

FIG. 5 is a top view of a round bale hay feeder of the present design.

Any shading and cross-hatching are not features of the design but are utilized to illustrate the surface contours of the round bale saddle feeder design in the drawings.
